UNITED STATES PATENT OFFICE.

SAMUEL WILLIAMSON, OF CINCINNATI, OHIO, AND GEORGE HORNUNG,
OF NEWPORT, KENTUCKY.

IMPROVEMENT IN HYDRANT STOP-BOXES.

Specification forming part of Letters Patent No. **148,102**, dated March 3, 1874; application filed December 15, 1873.

To all whom it may concern:

Be it known that we, SAMUEL WILLIAMSON, of Cincinnati, Ohio, and GEORGE HORNUNG, of Newport, Kentucky, have invented certain Improvements in Hydrant Stop-Boxes, of which the following is a specification:

Heretofore hydrant or gas stop-cock boxes have been constructed with a cover either loosely attached by means of lugs hooking beneath the top flange of the box or by a hinge allowing the same to lie loosely on the box, owing to which they are often tampered with by unauthorized persons.

Our invention consists, first, in locking the lid onto the box, so that it cannot be opened without the key; and, second, in a peculiar arrangement of parts for accomplishing this purpose.

In the drawings, Figure 1 is a plan view of our invention, showing the lid and box separated. Fig. 2 is a sectional view, showing the cover and box when locked.

A is the hydrant-box, which is constructed in the usual manner. B is the cover or lid, having on its upper surface the nut-cavity C, and cast on its under side the hollow guide D. Guide D is perforated at the end to allow the screw E to pass through, and on either side has an oblong aperture, through which the arms of the cross-bar F project. The screw E has a head, G, upon which the key H fits. The screw E is used to draw the ends of the cross-bar up against the inner flange I, and thereby hold the cover firmly in position. The cover has lugs K K on its under surface, projecting within the rim of the box.

The arrangement above described furnishes the means of readily adjusting the cover firmly to the box. It is first placed on the box, the ends of the cross-bar passing through the spaces between the parts of the inner flange I, then is turned through an angle of ninety degrees, more or less, when the cross-bar, owing to the fact that it is held in place by the hollow guide D, is turned also, the ends thus coming under the flange I. The screw is then turned by

means of the head and key, when the ends of the cross-bar are drawn up hard against the under side of the inner flange, thereby firmly securing the lid, so that, without the key, it will be very difficult to open the hydrant-box.

Instead of the lugs K, a concentric ring may be used, or the lid may be made so as to fit within the box and rest on the flange, though this form would be much more liable to rust onto the box. Any other equivalent form of key may be used. The screw we generally make of brass, as least liable to rust, but any other suitable metal may be used. The guide or cross-bar may be slightly varied in shape, if desired.

Though this box-cover is intended for water, yet it may be just as successfully used for gas, and, by slight variations, it may also be used for the oil-boxes for car-axles, &c.

What we claim is—

1. A locked hydrant-box, constructed with flange I, cross-bar F, internal screw, raising and lowering said cross-bar, and operated and locked by cap H, and cover B, cast with loose guide D upon its under side, so constructed and arranged as to operate the cross-bar F, substantially as and for the purpose hereinbefore set forth.

2. The combination of cross-bar F with cover B, when cast with guide D upon its under side, said guide having apertures to receive said cross-bar, and being so constructed as to operate the same, substantially as hereinbefore set forth.

3. The combination of cross-bar F and cover B, when cast with guide D upon its under side, said guide having apertures to receive said cross-bar, and being so constructed as to operate the same, with internal screw E, substantially as shown, and for the purpose hereinbefore set forth.

SAMUEL WILLIAMSON.
GEO. HORNUNG.
